US00D980498S

(12) **United States Design Patent** (10) **Patent No.:** **US D980,498 S**
Shi (45) **Date of Patent:** **** Mar. 7, 2023**

(54) **LAMP**

(71) Applicant: **SHENZHEN TAOTENG TECHNOLOGY CO., LTD.**, Shenzhen (CN)

(72) Inventor: **Jun Shi**, Shenzhen (CN)

(73) Assignee: **SHENZHEN TAOTENG TECHNOLOGY CO., LTD.**, Shenzhen (CN)

(**) Term: **15 Years**

(21) Appl. No.: **29/821,457**

(22) Filed: **Dec. 30, 2021**

(51) **LOC (14) Cl.** **26-05**

(52) **U.S. Cl.** **USPC** **D26/93; D26/104**

(58) **Field of Classification Search**

Primary Examiner — Nathan M Johnston

(57) **CLAIM**

The ornamental design for a lamp, as shown and described.

DESCRIPTION

FIG. 1 is a perspective view of a lamp showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the lamp that form no part of the claimed design.

1 Claim, 8 Drawing Sheets
